UNITED STATES PATENT OFFICE.

CHARLES KNAPP, OF BROOKLYN, NEW YORK.

DESIGN FOR A RING.

SPECIFICATION forming part of Design No. 26,392, dated December 15, 1896.

Application filed September 18, 1896. Serial No. 606,304. Term of patent 3½ years.

To all whom it may concern:

Be it known that I, CHARLES KNAPP, a citizen of the United States, residing at Brooklyn, county of Kings, and State of New York, 5 have invented and produced a new and original Design for Rings, of which the following is a specification, reference being had to the accompanying drawings, wherein—

Figure 1 is an enlarged view of the design, 10 and Fig. 2 is a perspective view of the ring.

The design consists of a plastic ornament surrounding the head of the ring and connecting it to the band, whereby the effect of the setting is increased.

15 The leading feature of the design is a series of consoles arranged between the head and the joining-point of the band of the ring and diminishing in size successively from the head toward the band of the ring.

20 One end of the largest console next to the head of the ring is set in near proximity to the border of the head, whereas the connection between the other end of the console and the border of the head is effected by a volute 25 interposed between.

The design is symmetric in reversed order on both sides of the head of the ring.

The fields between the figures are matted and rosettes in the shape of a Maltese cross and diminishing in size successively from the 30 head toward the band of the ring are set in the fields.

The joint between the ornament and the band of the ring is made with a hyperbolic curve surrounding the terminus of the last 35 console, and the ground is filled with rays projecting from the terminus of the last console toward the curve.

The head of the ring represents an ellipse having its circumference formed of a chain 40 of scallops alternately reversed.

In the center of the head is an eight-pointed star with rays spreading from the center between the points. The inner points of the star form grips for a solitaire set in the center of the head. 45

I claim—

The design for rings as herein shown and described.

CHARLES KNAPP.
